P. R. SMITH ET AL
OPTICAL ALTITUDE COMPUTING DEVICE

3,153,857

Filed Aug. 4, 1961

FIG. 1. A perspective view of a window frame assembly. The frame is made of vertical and horizontal bars. A vertical bar on the right is labeled 13. A horizontal bar at the bottom is labeled 12. A horizontal bar on the left is labeled 11. A diagonal bar labeled 16 connects the top of bar 11 to the bottom of bar 13. A horizontal bar labeled 10 is attached to bar 16. A horizontal bar labeled 15 is attached to the bottom of bar 13. A small rectangular component labeled 15 is attached to bar 15. A vertical bar labeled 17 is attached to bar 11. A horizontal bar labeled 18 is attached to bar 17. A circular component labeled 19 is attached to bar 18. A horizontal bar labeled 20 is attached to bar 19. A horizontal bar labeled 21 is attached to bar 20. A horizontal bar labeled 22 is attached to bar 21. A horizontal bar labeled 23 is attached to bar 22. A vertical bar labeled 14 is attached to the top of bar 13. A vertical bar labeled 16 is attached to the top of bar 14. A vertical bar labeled 17 is attached to the top of bar 14. A vertical bar labeled 18 is attached to the top of bar 17. A vertical bar labeled 19 is attached to the top of bar 18. A vertical bar labeled 20 is attached to the top of bar 19. A vertical bar labeled 21 is attached to the top of bar 20. A vertical bar labeled 22 is attached to the top of bar 21. A vertical bar labeled 23 is attached to the top of bar 22. A vertical bar labeled 24 is attached to the top of bar 23. A vertical bar labeled 25 is attached to the top of bar 24. A vertical bar labeled 26 is attached to the top of bar 25. A vertical bar labeled 27 is attached to the top of bar 26. A vertical bar labeled 28 is attached to the top of bar 27. A vertical bar labeled 29 is attached to the top of bar 28. A vertical bar labeled 30 is attached to the top of bar 29. A vertical bar labeled 31 is attached to the top of bar 30. A vertical bar labeled 32 is attached to the top of bar 31. A vertical bar labeled 33 is attached to the top of bar 32. A vertical bar labeled 34 is attached to the top of bar 33. A vertical bar labeled 35 is attached to the top of bar 34. A vertical bar labeled 36 is attached to the top of bar 35. A vertical bar labeled 37 is attached to the top of bar 36. A vertical bar labeled 38 is attached to the top of bar 37. A vertical bar labeled 39 is attached to the top of bar 38. A vertical bar labeled 40 is attached to the top of bar 39. A vertical bar labeled 41 is attached to the top of bar 40. A vertical bar labeled 42 is attached to the top of bar 41. A vertical bar labeled 43 is attached to the top of bar 42. A vertical bar labeled 44 is attached to the top of bar 43. A vertical bar labeled 45 is attached to the top of bar 44. A vertical bar labeled 46 is attached to the top of bar 45. A vertical bar labeled 47 is attached to the top of bar 46. A vertical bar labeled 48 is attached to the top of bar 47. A vertical bar labeled 49 is attached to the top of bar 48. A vertical bar labeled 50 is attached to the top of bar 49. A vertical bar labeled 51 is attached to the top of bar 50. A vertical bar labeled 52 is attached to the top of bar 51. A vertical bar labeled 53 is attached to the top of bar 52. A vertical bar labeled 54 is attached to the top of bar 53.

FIG. 2. A geometric diagram showing a triangle ABC. Point O is on the base AB. Point H is on the side AC. A horizontal line segment connects O and H. The distance from O to H is labeled d. The distance from O to B is labeled D/2.

OPTICAL ALTITUDE COMPUTING DEVICE
Paul R. Smith, Quarters 116, Aberdeen Proving Ground,
Md., and Joseph W. Mather, P.O. Box 143, Aberdeen,
Md.

Filed Aug. 4, 1961, Ser. No. 129,484

1 Claim. (Cl. 33—64)

(Granted under Title 35, U.S. Code (1952), sec. 266)

The invention described herein may be manufactured and used by or for the Government for governmental purposes without the payment to us of any royalty thereon.

This invention relates to an improved means for measuring the maximum altitude attained by a visually observed missile, and more particularly it relates to a compact, portable device for determining the maximum altitude attained by ground launched pyrotechnic signals.

It is well known in the art of ammunition surveillance that functional tests, are performed at regular, periodic intervals on random selections from the various manufactured lots of ordnance explosive materiel in an effort to detect premature deterioration in its earliest stages and thus promote safety and combat readiness. One such test consists of measuring the maximum altitude obtainable from randomly selected pyrotechnic items from each manufactured lot undergoing inspection.

A loss of altitude in any given lot, as compared to the altitude attained when the lot was initially manufactured, evidences some degree of deterioration of the propelling explosive. Such information reflects the rate of propellant deterioration and accordingly facilitates the proper selection of which ammunition lots are to be expended first, and which lots are to be destroyed or stored, with special attention to the increased fire hazard due to premature deterioration.

Accordingly, it is an object of this invention to provide a light weight, portable device for measuring the maximum altitude of pyrotechnic ammunition items.

Another object is to render such altitude measurements highly accurate by utilizing two such devices in conjunction with each other while located a given distance apart.

Other objects and features of the invention will become apparent to those skilled in the art as the disclosure is made in the following description of a preferred embodiment of the invention as illustrated in the accompanying drawing wherein:

FIGURE 1 illustrates an isometric projection of a single optical altitude computer; and

FIGURE 2 illustrates a schematic representation of the manner in which two altitude computing devices are used in relation to the pyrotechnic launching site.

Referring now in greater particularity to the drawing, there is shown in FIGURE 1 a collapsible optical computing device 10 comprised of a base 11 supported by three adjustable legs 12. The use of three adjustable legs provides for stability and ease of leveling. Near one end of base 11 is a perpendicularly upstanding U-shaped frame 13 carrying a window 14 of Plexiglas or other suitable material rigidly connected thereto. Hinges 15 connect frame 13 to base 11 and provide for collapsibility therebetween. Latching arms 16 provide for rigid support of frame 13 in its upstanding position.

Near the other end of base 11 is a collapsible viewing column 17 having an eyepiece 18 mounted on the top thereof. The eyepiece, formed of plastic or other suitable material, has a plurality of equally spaced apertures 19 near its periphery and a small circular aperture 20 located at its center. The viewing column 17, adapted for pivotal raising and lowering about hinge 22, is retained in its upright position by stabilizing hook 21.

2

Base 11 contains a recess 23 which accommodates eyepiece 18 in its lowered or collapsed position.

Window 14 has engraved thereon a plurality of parallel, horizontally spaced lines. Each of these lines is numbered so as to correspond to the angle formed between an imaginary horizontal plane through aperture 20 and line of sight through aperture 20 and a particular engraved line on window 14. Thus, as shown in FIGURE 1, the lines engraved on window 14 are numbered from 18 to 54 thereby indicating, for example, that when viewed through aperture 20, any objective coincident with the line of sight passing through line numbered 40 would indicate that objective to be at an elevation of 40° above an imaginary horizontal plane passing through aperture 20.

Referring now to FIGURE 2, "O" represents the launching site of the pyrotechnic ammunition device to be tested. "A" and "B" represent the locations of two optical altitude computers constructed according to the present invention. The flight of the pyrotechnic device follows trajectory "OD," and the maximum altitude attained is simultaneously observed by both computing devices through apertures 20 and windows 14 and recorded. The angles "α" and "β" are measured from each computing device location by the operators first observing the bath of the missile through large apertures 19 and then noting through aperture 20 the highest engraved line 18 to 54 on window 14 attained by the airborne device. It is of course understood that the trajectory of the pyrotechnic device should lie substantially in the same vertical plane as that of the two computers.

The tangents for each of the angles "α" and "β" can easily be expressed as follows:

$$35 (1) \quad \left(\frac{D}{2} + d \right) (\tan \alpha) = H$$

$$(2) \quad \left(\frac{D}{2} - d \right) (\tan \beta) = H$$

40 Solving Equation 2 for "d" and substituting in Equation 1 yields:

$$(3) \quad H = D \frac{\tan \alpha \tan \beta}{\tan \alpha + \tan \beta}$$

45 Equation 3 can be further simplified to yield:

$$(4) \quad H = \frac{D}{\cot \alpha + \cot \beta}$$

50 Knowing the values of "α" and "β," as determined from the computing devices hereinabove described, the values of the respective cotangents can be easily determined from a table of trigonometric functions. The distance "D" being known, it becomes a relatively simple matter to substitute these quantities into Equation 4, above, and thereby determine "H."

55 Thus, it can now be easily seen that this invention provides a simple and effective apparatus for determining the maximum altitude of a visually observed pyrotechnic projectile.

60 Numerous tests have indicated that novice operators of this computer device can easily read the maximum trajectory within 1° on the window scale provided. Accordingly, based on a 1° human accuracy deviation, this invention is accurate to within 2.03%.

Various modifications are contemplated and may obviously be resorted to by those skilled in the art without departing from the spirit of the invention or the scope of the appended claim, as only a preferred embodiment has been disclosed.

70 What is claimed and desired to be secured by Letters Patent of the United States is:

An optical elevation computer system comprising a

pair of mutually facing computing devices spaced apart a predetermined distance and trained toward a common object, each computing device comprising a planular base having adjustable support members connected to the underside of said base to maintain the base in a level horizontal position, a U-shaped support frame having a recessed track within its inner periphery, rigid support hinges attached at one end to said planular base and connected at the other end to the support frame to permit said frame to fold upon said base when not in use, a removable transparent scale member slidable within the track of the support frame, said transparent scale member being properly graduated by horizontal lines engraved thereon, a collapsible viewing column attached to said planular base, an apertured eyepiece positioned on top of said column for viewing said object through the transparent scale, a recess within said base to receive the eyepiece when said column is in a folded position and the distance between said lines on the graduated

5

transparent scale representing one degree difference in elevation when viewed through the apertured eyepiece whereby the angle of elevation from each eyepiece may be read on the respective transparent scales of each computing device and from which the altitude of the object may be calculated by any desired method.
